UNITED STATES PATENT OFFICE.

JUAN A. CUEVAS, OF NEW YORK, N. Y.

REFILLABLE SHAVING BRUSH.

Application filed July 5, 1927. Serial No. 203,477.

The present invention is concerned with a refillable shaving brush consisting of a detachably connected bristle tuft and handle.

Preferably the bristle tuft is comparatively inexpensive so that it may be inserted in the handle, used once and discarded, and the handle provided with means for preventing rotary movement of the bristle tuft when the latter has been entered into the handle socket.

10 An object of the invention is to provide a sanitary brush of this character which may be manufactured with great economy, which will be of simple, practical construction, efficient in use, neat and attractive in appearance, and well suited to satisfy sanitary requirements.

With the above noted and other objects in view, the invention consists in certain novel features of construction and combinations 20 and arrangements of parts, as will be more fully hereinafter set forth and pointed out in the claims. The invention may be more fully understood from the following description in connection with the accompanying 25 drawings, wherein—

Fig. 1 is a view in elevation of a shaving brush embodying the present invention.

Fig. 2 is a longitudinal sectional view therethrough with a part of the bristle tuft 30 broken away to expose the construction of the handle socket.

Fig. 3 is an enlarged transverse sectional view on the line 3—3 of Fig. 2.

Fig. 4 is a perspective view showing the 35 bristle tuft removed from the handle.

In the drawings I have used the reference numeral 10 to designate the handle in which a bristle tuft 11 is adapted to be removably inserted. The handle may be of more or less 40 conventional external appearance, and is provided at one end with a socket 12, this socket being internally shaped to prevent the rotation of a bristle tuft therein. Preferably the socket is simply provided with a plurality of spaced inwardly projecting longitudinally extending integral ribs 13.

The bristle tuft which I propose to use 50 simply consists of a bunch of bristles of similar length tied together at their intermediate portion by a wire, cord or similar securing device 14. The bristle tuft is folded upon itself about the cord 14 and inserted in the socket.

The bristle tuft is prevented from drop-

ping out of the socket by the friction exerted 55 by the inherently resilient bristles on the socket walls, and rotation of the bristle tuft is prevented by the interengagement of the ribs 13 with the bristles.

Preferably the bristle tuft is of some cheap 60 material which may be used once and discarded, or if desired, the bristle tuft units may be readily removed from the handle, sterilized and re-used.

From the foregoing description it will be 65 seen that I have provided an extremely simple and practical device, the bristle tuft being capable of economical manufacture because it consists of simply a bunch of bristles tied together in the middle. Obviously the handle 70 may be cast or molded inexpensively, and the operation of inserting or removing the bristle tuft is a simple one in which the bristle tuft is simply doubled upon itself and forced into the socket. There is no need for operating 75 screws or various supplemental bristle tuft attaching means such as is now commonly employed in connection with removable tufts.

Obviously, various changes and alterations 80 might be made in the general form and arrangement of the parts described without departing from the invention. Hence I do not wish to limit myself to the details set forth, but shall consider myself at liberty to make such changes and alterations as fairly fall 85 within the spirit and scope of the appended claims.

I claim:

1. A refillable brush handle having an internally longitudinally ribbed socket therein 90 adapted to receive a folded bristle tuft and retain said bristle tuft against rotary movement by the interengagement of the ribs and bristles.

2. A shaving brush including a handle having a brush receiving socket therein, a removable bristle tuft comprising a bundle of bristles of approximately equal length bound in the middle, doubled on itself and inserted in the socket, the inherent resiliency of the 100 bristles tending to cause frictional engagement between the bristle tuft and the socket walls to prevent the bristle tuft from falling out when the handle is inverted, the socket being internally longitudinally ribbed to prevent rotation of the bristle tuft therein. 105

JUAN A. CUEVAS.
